(57) **CLAIM**

The ornamental design for a smart watch band with protective case, as shown and described.

DESCRIPTION

FIG. 1 is a front, top, and right perspective view of a first embodiment of a smart watch band with protective case showing my new design;

FIG. 2 is a rear, bottom, and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the smart watch band with protective case thereof where the smart watch band with protective case is in a folded state;

FIG. 10 is a front, top, and right perspective view of a second embodiment of a smart watch band with protective case showing my new design;

FIG. 11 is a rear, bottom, and left perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is a perspective view of the smart watch band with protective case thereof where the smart watch band with protective case is in a folded state.

The dash-dash broken lines in the drawings depict portions of the smart watch band with protective case or environmental subject matter that form no part of the claimed design.

1 Claim, 18 Drawing Sheets
